UNITED STATES PATENT OFFICE.

JOHN A. BELT, OF WASHINGTON, DISTRICT OF COLUMBIA.

MOISTENING DEVICE.

1,388,399.

Specification of Letters Patent. Patented Aug. 23, 1921.

Application filed April 23, 1920. Serial No. 376,061.

To all whom it may concern:

Be it known that I, JOHN A. BELT, a citizen of the United States, residing at Washington, in the District of Columbia, 5 have invented a new and useful Moistening Device, of which the following is a specification.

It is the object of this invention to provide a simple means whereby moist air may 10 be taken from the radiator of an internal combustion engine and be delivered to the carbureter thereof.

The invention is shown in a single figure constituting a vertical section taken through 15 the upper member of a radiator to the rear of the honeycomb section, a portion of the lower member of the radiator being broken away.

The numeral 1 denotes the upper member 20 of a radiator, having a filling neck 2. The lower member of the radiator is shown at 3, the members 1 and 3 being connected by a tubular radiator core 4. The lower member 3 embodies an outlet 5. An overflow 25 pipe 6 leads from the upper member 1 as usual.

Partitions 7 extend inwardly from the side portions of the upper member 1 and define a chamber 8, the inner ends of the 30 partitions slanting downwardly as shown at 9. The parts 9 are connected by a screen 10. Above the screen, the front and rear walls of the member 1 are connected by an upwardly curved baffle 11. An air outlet 35 pipe 12 extends upwardly through the bottom of the member 1 and through one of the partitions 7 into the chamber 8 and carries at its upper end, a screen 14. The lower end of the pipe 12 is connected by 40 a clamp 15 or otherwise to a tube 16 leading to the carbureter or to some part which discharges into the carbureter. An air inlet pipe 17 opens laterally at its lower end, as shown at 18 through the lower member 3

and extends upwardly through the member 45 1 into the chamber 8.

In practical operation, air enters the lower end of the pipe 17 and moves upwardly into the chamber 8, the air being heated more or less by the relatively hot 50 water at the top of the radiator in the upper member 1. The moisture from the water in the upper member 1 of the radiator passes through the screen 10 and mingles with the air, the warm moist air passing 55 into the pipe 12 through the screen 14, and leaving by way of the tube 16. Since the ends of the partitions 7 are downwardly inclined as shown at 9, the screen 10 is located relatively close to the surface of the 60 water and will be kept in a moist condition. If the water in the upper member 1 should happen to slop through the screen 10, the water cannot reach the air pipe 17 or the tube 12, but will be returned promptly 65 to the lower portion of the member 1 owing to the inclination of the ends 9 of the partition 7, and owing to the presence of the baffle 11.

I claim:—

A radiator comprising an upper member; partitions in said member and separating the same into upper and lower chambers, the inner ends of the partitions converging downwardly; a screen connecting the said 75 ends of the partitions; a baffle in the upper chamber above the screen and between the said ends of the partitions; an air inlet for the upper chamber; and an air outlet therefor.

In testimony that I claim the foregoing as my own, I have hereto affixed my signature in the presence of two witnesses.

JOHN A. BELT.
